UNITED STATES PATENT OFFICE.

DEAN A. CATO, OF SPRINGFIELD, ILLINOIS, ASSIGNOR OF ONE-HALF TO FRANK E. VAN WINKLE, OF SPRINGFIELD, ILLINOIS.

IRONING-BOARD.

1,279,986.

Specification of Letters Patent. Patented Sept. 24, 1918.

Application filed March 20, 1918. Serial No. 223,570.

To all whom it may concern:

Be it known that I, DEAN A. CATO, a citizen of the United States, residing at Springfield, in the county of Sangamon and State 5 of Illinois, have invented new and useful Improvements in Ironing-Boards, of which the following is a specification.

This invention relates to an ironing board of the type which is intended when in use 10 to be detachably connected with a support such as a wall or the like.

The primary object of the invention is to provide the board with a hingedly and detachably mounted strip of novel construction 15 for engagement with a securing element upon a support and with a resilient bail similarly mounted upon the board.

With these and other objects in view, the invention resides in the novel combination 20 and arrangement of parts, which will be hereinafter described and particularly pointed out in the claim.

The preferred embodiment of the invention has been illustrated in the accompanying 25 drawings, although no restriction is necessarily made to the precise details of construction therein shown, as changes, alterations, and modifications within the scope of the claim may be resorted to when 30 desired.

In the drawings:—

Figure 1 is a perspective view of an ironing board constructed in accordance with the invention and showing the same connected with a support.

Fig. 2 is a similar view of the board and showing the attaching plate and bail folded thereon.

Fig. 3 is a vertical longitudinal section 40 through a portion of the board and the attaching strip thereon.

Like characters of reference denote corresponding parts throughout the several views in the drawings.

Referring now to the drawing in detail 45 the letter A designates an ironing board which is of the shape of those now in common use and has detachably connected therewith adjacent the larger end of the board a yoke 5. An attaching plate 6 is swingingly

and detachably connected with a yoke 5 by a hook 7 which is formed from one end of the plate and has the bill thereof extending toward the body of the plate to provide a restricted passage through which the cross bar of the yoke must be passed before the yoke can be detached from the plate 6. The plate has formed therein adjacent its other end a key hole slot 8 whereby the plate may be detachably connected with a securing element such as a screw or the like upon a support as shown in Fig. 1 in the drawing. A tongue 9 is struck from the plate 6 and is bent to form a hook.

The hook which is formed from the 65 tongue 9 is adapted when the board is in use to be connected with a bail 10 which is formed from resilient material and has the arms 11 thereof bent adjacent their outer ends to provide fingers 12 which extend within boxings 13 secured to the bottom face of the board A as shown.

Through the above described manner of connecting the bail with the board A it is apparent that the bail is not only swingingly connected with the board, but by spreading the arms of the bail apart the fingers may be withdrawn from the boxing 13 to permit the bail to be connected with the board as shown in Fig. 2 in the drawing 70 when the board is in use, thus enabling the bail and attaching strip to be folded upon the board in such a manner that the board will occupy very little space when not in use.

When the board is connected with the support as shown in Fig. 1 in the drawing and it is desired to remove the board therefrom, the attaching plate is disconnected from the securing element upon the support 90 and folded upon the board. The bail 10 is now disengaged from the boxing 13 and again engaged therewith so the bail will lie upon the side of the board opposite that in contact with the plate 6.

From the foregoing description taken in connection with the accompanying drawing it is apparent that an ironing board is provided which may be detachably connected with a support such as a wall or the 100

like by attaching means of novel construction.

Having thus described the invention, what is claimed as new, is:

5. An ironing board having a bail swingingly and detachably connected therewith, a yoke adjacent one end of said board, a

plate having a key hole slot therein, a hook at one end of said plate engaging said yoke, and a tongue struck from said plate adapted to be engaged with said bail.

In testimony whereof I affix my signature.

DEAN A. CATO.
